EZECHIEL WEINTRAUB, OF LYNN, MASSACHUSETTS, ASSIGNOR TO GENERAL ELECTRIC COMPANY, A CORPORATION OF NEW YORK.

METALLIC ELECTRODE.

1,116,960.

Specification of Letters Patent.

Patented Nov. 10, 1914.

Application filed April 5, 1912. Serial No. 688,687.

To all whom it may concern:

Be it known that I, EZECHIEL WEINTRAUB, a citizen of the United States, residing at Lynn, county of Essex, State of Massachusetts, have invented certain new and useful improvements in Metallic Electrodes, of which the following is a specification.

My present invention relates to electrodes for use in vapor electric apparatus, particularly in mercury arc rectifiers.

The invention has for its object to provide an electrode which operates as positive electrode or anode which shall be free from the tendency of becoming the seat of an arc when made negative in the presence of mercury in an exhausted space, and which shall not give rise to electrical disturbances such as "fading." These objects are accomplished by making the anodes of the apparatus of metallic tungsten, preferably, drawn tungsten.

I have discovered that it is incomparably more difficult to establish a cathode spot of an arc in an exhausted space on the surface of tungsten than on the surface of any other material that I have tried. To illustrate this, let us suppose that a solid material such as carbon or iron, is brought in contact with mercury in an exhausted space, the solid material being connected to the negative side and the mercury to the positive side of a source of current. Even at voltages as low as 100 volts and lower, a regular mercury arc is formed with the cathode spot on the solid material. With tungsten anodes it is impossible to get the cathode spot to form even with 500 volts and with very little resistance in series. With higher voltages the arc will start with a cathode spot on the glass into which the leading-in wire is sealed rather than on the tungsten. This method of contact is the easiest way of producing a cathode spot on a solid metallic material. In the rectifier the conditions are not so favorable to the formation of a cathode spot on the solid material and it takes a high voltage to produce it, even in case of iron or graphite. The quantitative difference between the ease of formation of a cathode spot on iron, graphite, etc., as compared to tungsten, however, remains the same as that illustrated by the contact method.

The phenomenon of reverse arcing is very troublesome and limits the application of

the rectifier with any given voltage to a certain maximum current, this current becoming smaller as the voltage is increased. Any device that makes this reverse arcing more difficult is consequently of essential importance to the development of the rectifier. In attempting to apply this valuable property and to use tungsten as anode material in the high voltage rectifier, I have found the unexpected result that it is necessary to make tungsten anodes of a larger radiating surface than customarily employed when the anodes consist of graphite or iron. Unless this is done the rectifier provided with tungsten anodes will give trouble due to "fading".

The drawings illustrate by way of example, the rectifier tube provided with anodes of tungsten. The rectifier tube with container shown in the drawing is of a common form now well known in the art and requires no special description. The mercury cathode of the rectifier tube is at 1 and the starting electrodes at 2 and 3. The main anodes are arranged as usual in the upper ends of the outwardly and upwardly extending arms 4 and 5. The anodes themselves as indicated by the numerals 6 and 7, and as has been mentioned, are made of metallic tungsten. The anodes are indicated as being hollow and as practically filling the upper part of the anode tubes in order to provide for more effective heat radiation.

As well understood by those skilled in the art, the term "fading" is applied to a condition in a rectifier which causes the arc to start at a progressively higher voltage as it shifts from anode to anode. In other words, the tubes require a progressively higher voltage to operate, thus utilizing smaller and smaller proportion of the alternating current. The tube finally goes out because the current utilized is not sufficient to maintain the arc. I believe this difficulty with tungsten anodes of the usual size to be due to the fact that tungsten anodes operate at a higher temperature than graphite anodes of the same size, possibly due to the fact that tungsten is a poorer radiator of heat energy than graphite and most other materials. I, therefore, so proportion the extent of the anode surface with respect to the capacity or rating of the device that the anode will operate at a temperature below cherry red. As the anodes are not artificially

cooled they necessarily are heated by the arc to a temperature above the boiling point of mercury in a vacuum.

In mercury arc devices provided with 5 anodes of tungsten a further advantage is secured by the fact that the vacuum is not affected by the giving off of gases and, therefore, the tube is more readily exhausted as well as maintaining a more permanent 10 vacuum during its operation.

The method of making anodes of malleable or drawn tungsten is described in patent of W. D. Coolidge, No. 1,082,933. It is not absolutely necessary, however, that the 15 anodes shall consist of drawn tungsten but they may be made of sintered tungsten by pressing powdered tungsten into the desired shape by a suitable binder and then removing the binder by methods now well understood in the art.

The appended claims are directed to the structural features of the rectifier tube, but claims on broader features of my invention such as the rectifying system are not made 25 herein but are made in other applications and especially in application, Serial No. 149,084, filed March 23, 1903.

What I claim as new and desire to secure by Letters Patent of the United States, is:—

30 1. The combination of an evacuated container, a cathode of easily vaporizable mate-

rial and a coöperating anode consisting of tungsten and having a heat dissipating capacity proportioned with respect to the operating capacity of the device to enable said 35 anode to operate below cherry red heat, but above the boiling point of mercury in a vacuum.

2. The combination of an evacuated container having a mercury cathode and electrodes operating as anodes with respect to said cathode but subjected to differences of potential with respect to each other, said anodes consisting of tungsten and having a sufficient heat dissipating capacity to enable them to operate at a temperature below 40 cherry red heat, but above the boiling point of mercury in a vacuum.

3. The method of preventing fading of a periodically shifting vapor electric arc operated between a mercury cathode and co-operating tungsten anodes alternating in potential which consists in dissipating heat from said anodes at a rate proportioned to maintain said anodes at a temperature below 45 cherry red.

In witness whereof, I have hereunto set my hand this third day of April, 1912.

EZECHIEL WEINTRAUB.
